UNITED STATES PATENT OFFICE.

ANATOL GOLLOS, OF CHICAGO, ILLINOIS.

TRACK APPARATUS FOR SIGNAL OR STOP SYSTEMS.

1,163,595.

Specification of Letters Patent. Patented Dec. 7, 1915.

Application filed November 23, 1912. Serial No. 733,024.

To all whom it may concern:

Be it known that I, ANATOL GOLLOS, a citizen of the United States, residing at Chicago, in the county of Cook and State of Illinois, have invented certain new and useful Improvements in Track Apparatus for Signal or Stop Systems, of which the following is a specification.

The use of an intermittent third rail, or contact rail as it is more commonly called, in connection with railway signal systems or stop systems, has heretofore been proposed or adopted. Ordinarily these contact rails or contact members comprise relatively short sections, usually arranged adjacent to the end of a block and supplied with a feed wire whereby the rail may be energized, these rails operating in conjunction with contact shoes or contact devices arranged on the car or locomotive. An objection to the usual arrangement of such contact rails and track circuits as heretofore arranged has been that the contact rail might become torn out entirely, or moved to such an extent that the contact shoes would not touch the same, without affecting the system so that a warning would be given of the displacement of such rail.

The principal object of the present invention is to arrange the wiring of the track system so that the tearing out or displacement of the contact rail will act upon the track circuits so that a proper warning or signal will be given.

I have illustrated my invention in the accompanying drawings in which,

Figure 1 is a diagrammatical view of a track system embodying this invention; Fig. 2 is an end view of an undercontact rail showing one method of securing a circuit wire thereto; Fig. 3 is a side view of the parts shown in Fig. 2; Fig. 4 is an end view of a contact rail for an overrunning contact shoe showing the circuit wire attached thereto; and Fig. 5 is a side view of the parts shown in Fig. 4.

As indicated in these drawings, 6 represents one of the track rails which is insulated at the ends of the blocks, and 7 represents the other rail which is continuous. Each block is provided with a track battery 8 which is connected to the rails 6 and 7 by wires 9 and 10 adjacent to the exit ends of the blocks. The system shown in Fig. 1

is intended for a double track road with the trains moving from left to right as indicated by the arrow, two stations A and B being shown. The apparatus at station A only, will be described, the corresponding parts at the different stations being lettered to indicate their location. One of the terminals of a relay 11^a is connected by means of a wire 12^a to the rail 7, the other terminal is connected by means of a wire 13^a to the rail 6 at the right of the station. One of the switches or contacts 14^a of the relay 11^a is connected by means of a wire 15^a to the wire 12^a. Such switches or contacts are commonly designated as the relay armature which term will be used hereinafter for such contacts. The other terminal of this armature is connected by means of a wire 16^a with a battery or other suitable source of electricity 17^a. The other terminal of this battery is connected by means of a wire 18^a to the second armature of the corresponding relay at the next station to the left. This second armature 19^a at station A is connected by means of a wire 20^a to the contact rail or contact device 21^a which contact rail serves to coöperate with a contact shoe or equivalent device on a car or locomotive. The opposite terminal of the armature 19^a is connected by means of a wire 18^b with the battery 17^b at station B.

It will be readily seen that with the parts in normal condition the relay 11^a receives current from the battery 8^b adjacent to station B, the circuit being as follows: from battery 8^b, wire 9, rail 6, wire 13^a, relay 11^a, wire 12^a, rail 7, wire 10 back to battery. As long as the circuit remains closed the relay will be energized which will hold its armatures closed so that the contact rail 21^a will be energized by the battery 17^b, the circuit being as follows: contact rail 21^a, wire 20^a, armature 19^a, wire 18^b, battery 17^b, wire 16^b, relay 14^b, wire 15^b, wire 12^b to rail 7, the arrangement being such that the circuit may be closed from the contact rail to the rail 7 through the locomotive. It will be readily seen that if the battery 8^b is short circuited, which would occur by the presence of a car or train between the stations A and B, or if the circuit from the battery to the relay is interrupted, the relay would drop and would open the circuit to the contact rail. I do not herein claim this general system,

such system being shown and claimed in my co-pending application, filed July 10, 1912, Serial No. 708,655, but illustrate so much of the system as a whole as appears necessary 5 to clearly explain the present improvement. It will be noted that if there were no other connection between the contact rail 21^a and the system except through the wire 20^a, the contact rail could be torn out or displaced 10 without in any way affecting the balance of the system, and if a train passed the block where the rail was torn out or displaced it would receive no warning signal or would not be stopped. In order to overcome this 15 objection I carry the wire 12^a alongside the rail 21^a and secure it thereto in any convenient manner so that if the rail is torn away or displaced it will break the wire and thereby open the circuit from the track battery to the relay 11^b. If desired, a frangible 20 link or other connector such as indicated at 22 may be arranged in the wire 12^a so that it will be broken instead of the wire. It will be seen that when the relay opens, it will 25 open the circuits through both of its armatures and will thereby deenergize the contact rail at the next station to the left. For instance, if the relay 11^b is opened the contact rail 21^a will be deenergized on account of 30 opening the circuit through the armature 14^b. This will cause a train approaching from the left to be stopped or signaled at the next station to the one where the contact rail is torn out or displaced and the engineer or operator may then proceed under 35 caution or according to proper train rules until the difficulty is located.

When an under-contact rail, such as indicated at 23 in Figs. 2 and 3 is used, such 40 rail is usually protected by a wooden box or cover 24. In this instance, the wire 12^a may be carried along the side of the box and held in position by means of a molding 25.

With an over-contact rail, such as indicated at 26 in Figs. 4 and 5, blocks 27 may be secured to the web of the rail at intervals and a molding 28 attached to these blocks for receiving the wire 12^a. It will be readily apparent that various methods may be 50 used for securing the circuit wire to the contact rail without departing from the spirit of this invention. Furthermore, my improved arrangement may be used with other track systems employing contact rails and 55 having suitable track circuits, the present system being merely illustrative of the general arrangement.

Having thus described my invention what

I claim and desire to secure by Letters Patent is:

1. In an apparatus of the character set forth, the combination of a contact rail and a conductor arranged and connected therewith so that if the rail is torn away or moved a substantial distance, the conductor will be 65 broken.

2. In track apparatus for signal or stop systems, the combination of a contact rail, means for supplying current to said rail, means for controlling the supply of current 70 to said rail, which includes a conductor arranged adjacent to the rail and connected therewith whereby if the rail is displaced the conductor will be broken.

3. In track apparatus of the character set 75 forth, the combination with a railroad track, of contact rails, means for supplying electricity to said rails, means for controlling the supply of electricity to said rails, said latter means including conductors having 80 portions thereof lying alongside the contact rails and attached thereto.

4. In a track apparatus of the character set forth, the combination with a railroad track, of a contact rail, a source of electricity, controlling devices and a circuit for supplying electricity to said contact rail under predetermined conditions, a portion of one 85 of the circuit wires being arranged along the contact rail and secured thereto so that if the rail is displaced the circuit which includes the wire secured to the rail will be broken.

5. The combination with a contact rail for 90 a track system, of a track circuit including a conductor which is attached to one of the track rails, and means for securing said conductor to the contact rail and insulating the same therefrom, whereby if the contact rail is torn away the conductor will be broken.

6. The combination with an intermittent 95 contact rail for railway stop systems, of a housing of insulating material extending substantially the full length thereof, and a circuit wire extending along the housing and 100 secured thereto.

7. The combination with a contact rail, of a track circuit including a conductor arranged adjacent to the rail and connected therewith, one end of said conductor being 110 secured to the track rail so that if the contact rail is moved the circuit will be broken.

ANATOL GOLLOS.
